By his Attorney:

UNITED STATES PATENT OFFICE.

LEO HASEL, OF SAN FRANCISCO, CALIFORNIA.

DESIGN FOR A SHOE-PLATE.

55,126.

Specification for Design.

Patented May 11, 1920.

Application filed October 31, 1919. Serial No. 334,868. Term of patent 14 years.

To all whom it may concern:

Be it known that LEO HASEL, a citizen of the United States, residing at San Francisco, State of California, has invented a certain new and original Design for a Shoe-Plate, of which the following is a specification, reference being had to the accompanying drawing, forming a part thereof.

Figure 1 is a view in front elevation of a shoe plate embodying my new design, and Fig. 2 is a view in side elevation of the plate.

I claim:

The ornamental design for a shoe plate, as shown.

In testimony whereof I hereunto affix my signature in the presence of two witnesses.

LEO HASEL.

Witnesses:

WM. B. HORNBLOWER,
MARY HASEL.
